DISPENSING CAP

Anthony Santore, 202 E. 29th St., Bronx, N.Y., and Eric De Kolb, 20 E. 53rd St., New York, N.Y.

Filed Sept. 10, 1964, Ser. No. 81,666

Term of patent 14 years

(Cl. D58—26)

We claim:

The ornamental design for a dispensing cap, as shown.
